UNITED STATES PATENT OFFICE.

JESSE W. PEDIGO, OF CHARITON, IOWA.

LIGHTNING-ARRESTOR OR LINE-DISCONNECTOR.

No. 919,069.

Specification of Letters Patent.

Patented April 20, 1909.

Application filed June 23, 1908. Serial No. 439,886.

To all whom it may concern:

Be it known that I, JESSE W. PEDIGO, a citizen of the United States, and a resident of Chariton, in the county of Lucas and 5 State of Iowa, have made certain new and useful Improvements in Lightning-Arresters or Line-Disconnectors, of which the following is a specification.

My invention relates to lightning arresters, 10 and more particularly to that class employed in connection with a telephone or other delicate instrument, susceptible to injury from the overcharging of its circuit.

The object of the invention is to provide a 15 device which is simple in construction, durable, and which is not liable to get out of order.

A further object of the invention is to provide a device in which a double disconnection is effected by one movement.

20 In order to carry out the objects of the invention, I have provided a circuit breaker which is designed to be attached on the exterior of a building and to be operated from the interior.

25 My invention is illustrated in the accompanying drawing, in which—

Figure 1 is a perspective view showing one embodiment of my invention. Fig. 2 is a side view of the device, and Fig. 3 is a view 30 of the interior of the porcelain base showing the discharging members.

Referring now to Fig. 1, A indicates an oblong porcelain base, upon which are secured the operative parts of the line disconnector. 35 These consist of a pair of Z-shaped members 1 and 1', secured at one end to the base plate A by means of the screws 2 and 2', which pass through the downwardly turned flanges 3 and 3'. The opposite ends terminate in the 40 upturned flanges 4 and 4', which constitute stop members as will be explained hereinafter.

Disposed above the members 1 and 1' are the L-shaped contact members 5 and 5'. 45 These are retained by means of the screws 6 and 6', which are passed through the discharge members 7 and 8 and which serve to electrically connect the discharge members with the contact pieces, as well as to secure 50 these parts to the base. The free ends of the L-shaped contact members 5 and 5' are bent upwardly at an angle and form cam members 9 and 9'.

The movable part of the disconnector 55 comprises an insulating block 10 of porcelain or other insulating material, provided at each

end with U-shaped contact members 11 and 11', which are secured to the block by means of the rivets 12 and 12'. The free upper ends of the U-shaped contact members 11 and 11' are bent downwardly at an angle to form cam members 13 and 13', arranged to coact with the cam members 9 and 9' on the contact pieces 5 and 5'. The lower parts of the contact members 11 and 11' are arranged to ride upon the Z-shaped contact members 1 and 1'.

The insulating block 10 is secured to a rod 14 by means of the clamping member 15, which is perforated to permit the passage of 70 the rod, and which is provided with a set screw 16 for permitting the adjustment of the insulating block with respect to the rod.

The rod 14 passes through an opening in the porcelain base A and is designed to extend through the wall of the building to which the device is attached, and it is provided with a push button 17, of hard rubber or other insulating material, and the guide member or escutcheon 18, which is designed 80 to be fastened to the wall on the interior of the building. The discharge plates 7 and 8 consist of two flat strips, preferably of brass, which are close enough together to permit a static discharge, but are separated far 85 enough to prevent the passage of ordinary currents.

In practice, the telephone is attached by means of the wires 19 and 19' to the lower binding posts 2, which are in electrical connection with the contacts 1 and 1'. The main line wire 20 is in electrical connection with the upper contact member 5, and the ground wire is connected to the binding post which holds the contact member 5'. 95 In order to prevent any damage being done through a spark between the discharge pieces, I have provided the asbestos sheet 21, which closely fits within the hollow base.

When the disconnector is to be used on 100 metallic lines, the binding posts 6 and 6' are both connected to the line wires. I then use the ground wire 22, see Fig. 3, which terminates in the strip 24 which is adjacent to, but not connected with, the discharge members 105 7 and 8. Any excess of current on either line will cause the potential of the discharge members 7 and 8 to become so high that it will leap across the small air gap between said members and the terminal 24, thereby 110 discharging into the ground.

Having thus described in detail the vari-

ous parts of the device, I will state the use of the same and will point out certain advantages over other devices of a similar character now in use.

5 The normal position of the operating parts of the device is shown in Fig. 1. In this figure the telephone is in a bridge between the main line and the ground. On indications of an approaching storm, the telephone can be 10 instantly disconnected, not only from the main line, but also from the ground wire, by simply pushing the button 17. The block 10 with its contact 11 is then forced out of engagement with the coöperating contacts 5 and 5', and both of the connections are 15 broken. Moreover, the contacts 1 and 1' serve as guide and supporting members for the insulating block 10, preventing the rotation of the latter, while the upwardly turned 20 ends 4 and 4' limit the movement of the block. When the storm is over the button 17 is pulled and the block 10, with its connecting strip 11, is forced between the contacts 5, 5' and 1, 1'. These contacts are preferably 25 made of spring brass, and by reason of the cam members 9 and 9', 13 and 13', the springs are forced apart and a good electrical connection is effected.

I claim—

30 1. In a line disconnector, an insulating base member, a pair of lower Z-shaped contact members, a pair of upper L-shaped contact members, a connecting member arranged to slide on said lower contact members and to effect electrical connection between said lower members and said upper members, and means for moving said contact member to effect disconnection between said upper and said lower contact members.

2. In a line disconnector, an insulating 40 base member, a pair of lower Z-shaped contact members, a pair of upper L-shaped spring contact members provided with upwardly turned ends, an insulating block provided with connecting pieces arranged to engage said upper and said lower members, and a rod secured to said block and extending through said base for moving said block and its connecting members into and out of engagement with said upper and lower contact 45 members. 50

3. In a line disconnector, an insulating base member, a pair of lower spring contact members, a pair of upper spring contact members, an insulating block supported on 55 said lower spring contact members, and provided with connecting strips, a rod secured to said block and passing through said insulating base for forcing said connecting strips between said upper and lower spring members, 60 and stops on said lower contacts for limiting the movement of said block.

4. In a line disconnector, an insulating base member, a pair of lower spring contact members, a pair of upper spring contact 65 members, an insulating block slidably supported on said lower spring contact members and provided with connecting strips arranged to engage certain upper and lower spring contact members, and a rod secured to said block 70 and passing through said insulating base for forcing said connecting strips between their respective upper and lower spring contact members.

JESSE W. PEDIGO.
